UNITED STATES PATENT OFFICE.

DAVID E. BLAIR, OF MONTREAL, QUEBEC, CANADA, ASSIGNOR TO EDWARDS & COMPANY, A CORPORATION OF NEW YORK.

ELECTRIC PUSH-BUTTON.

1,243,482.

Specification of Letters Patent. Patented Oct. 16, 1917.

Application filed April 10, 1915. Serial No. 20,380.

To all whom it may concern:

Be it known that I, DAVID E. BLAIR, a subject of the King of Great Britain, residing at Montreal, in the Province of Quebec and Dominion of Canada, have invented certain new and useful Improvements in Electric Push-Buttons, of which the following is a full, clear and exact description.

10 This invention relates to electric push buttons, the object being to provide a device of this character which is especially adapted to be installed in street cars for the use of passengers in signaling the motorman. 15 The device, however, embodies structural features which are advantageous in a push button wherever used, and therefore the use of my invention is not confined to street cars. In street cars it is a common practice to locate the push buttons in the posts or frames between the windows and since these posts are usually compound structures consisting of a main post in which the sashways are formed, and a cap or facing strip which is 20 usually molded for ornamental reasons and beneath which the wires leading to the button are housed, it is desirable to devise a construction of button which will permit of the ready removal of the cap strip and of 25 the button itself, for purposes of inspection, repair, or when the interior of the car is to be varnished. For this purpose, the button I have invented permits of the removal of the cap strip from the window 30 post without disturbing any part of the button itself; it also permits of the entire removal of the button without the disconnection of the wires leading thereto, or, if desired, the wires may be readily disconnected from the button without the aid of 35 tools, and the button in its entirety may be removed without disassembling. The construction also permits of the entire button being inserted in its seat in the post and 40 the terminals of the wires thereafter brought into association with it without the aid of tools. The details of construction will now be described in connection with the accompanying drawing, in which:

45 Figure 1 is a face view of a portion of a car window post with the cap strip removed, showing the body of the push button in place and connected with the wires, the finger-piece being removed from the button;

Fig. 2 is an enlarged section on line 2—2 of Fig. 1, and

Fig. 3 is a transverse section of the complete window post and through the center of the complete button.

The push button consists of a hollow cylindrical body portion 1 closed at its rear end and open at its front end. In the bottom of the chamber within this cylinder, is an annular groove 2 forming a seat for a spring 3 and two longitudinal passages 4 and 5 arranged on each side of the axis and leading rearward into two transverse rectangular passages 6 and 7 which extend through the body 1 and are arranged parallel to each other as shown by the dotted lines in Fig. 1. The finger-piece consists of the usual plunger 8 having a flange 9 which rests against the outer end of the spring 3, the finger-piece being normally held in its extended position by said spring and prevented from being forced out of the body 1 by a flanged metal collar 10 which over-reaches the flange 9 and extends a short distance along the outside of the body 1 with its edge crimped into a groove therein, as seen at 11. The body 1 and the finger-piece are both preferably of insulating material, such as hard rubber, fiber, or some suitable composition, and in the formation of the finger-piece there is preferably molded into it a yoke-shaped metallic connector 12, the curved portion of the connector being anchored in the finger-piece, while the two legs project rearward and enter, respectively, the passages 4 and 5, in which they have free play. It will be seen that with this construction, by pushing upon the finger-piece, the legs of the connector may be forced through the passages 4 and 5 until they enter the cross passages 6 and 7, respectively, and upon the removal of the pressure, the spring forces the finger-piece outward and withdraws the legs of the connector into the normal position shown in the drawings.

50 Each of the passages 6 and 7 is adapted to receive a spring contact clip 13. These clips are provided with folded spring contact ends 14 which rest immediately under the passages 4 and 5 in a position to be struck by the connector 12 in its forward movement. The outer end of the clips consist of tail pieces 15 to which the respective ends of

the wires 16 and 17 leading to the button are soldered. The openings of the passages 6 and 7 through which the spring clips enter are restricted by humps 17' over 5 which the spring must be forced in order to properly position it within the passage, and the spring is provided with a bent portion 18 conforming to this hump and adapted to saddle upon it to retain the spring in position. The extremities of the hump are, however, inclined so that by using force the spring can be withdrawn from the passage whenever desired.

In order to mount this button in the 15 window-post, a circular cavity or socket 19 is formed in the face of the main post 20, the depth thereof being just equal to the length of the cylindrical body 1 of the button, and the diameter being such as to permit 20 the button to neatly fit therein with sufficient friction to hold it firmly in place. The wires 16 and 17 extend as usual along a groove 21 in the face of the post 20, which groove leads to the socket or seat 19. The 25 end of such groove is, however, enlarged and deepened to form a triangular cavity 21', the bottom of which leads down to the bottom of the socket for the button. This triangular cavity accommodates 30 the tail-pieces 15 of the spring contacts which are bent at the point where they leave the passages 6 and 7 to extend outward along the inclined face of the cavity. 22 indicates the ornamental cap or facing strip which 35 is usually applied to the outer surface of the post 20 and held in place by screws. This cap at the point where the finger-piece of the button is located, is provided with cylindrical holes which are preferably equipped 40 with bushings or escutcheons 23. The finger-piece projects through this hole into position where it can be easily reached and pressed inward by the finger. It will be seen that when the button is thus operated, 45 the circuit through the two wires is closed by the connector 12, the legs of which, respectively, make contact with the two springs in the passages 6 and 7.

It will now be seen that the cap strip can 50 be removed and replaced without disturbing any part of the button; that after the cap strip is removed, the button can be bodily removed from its socket in the post either with or without first removing the spring 55 contacts from the passages 6 and 7, and that in order to separate the button from the wires, it is only necessary to pull out the spring terminals from the passages and this may be done without the aid of tools, the 60 return of the contacts being accomplished with equal facility. An advantageous feature of the button is the fact that the spring terminals attached to the wires are confined

in separate passages or chambers so that in case they should become broken, there is no 65 danger of a short circuit. Furthermore, a complete closure of the circuit is insured with each movement of the button because of the yielding contact terminals which permit the connector carried by the finger-piece 70 to move inward until both of its legs are squarely in contact with the springs. The button is simple and cheap to construct, it is not liable to get out of order, and is readily installed.

I claim:—

1. In combination, a pair of wires having spring contact terminals permanently secured to the ends of said wires, a push button comprising a body portion having two 80 separate passages therein, said pair of spring contact terminals fitting into said passages and held in position therein only by the pressure exerted by said terminals upon the walls of said passage, a finger-piece 85 for the push button mounted on said body portion and carrying a connector for bridging said contact terminals.

2. In combination, a pair of wires having resilient contact terminals permanently secured to the ends thereof, a push button having separate passages therein, said contact terminals being fitted into said passages and held in position therein only by the engagement of said terminals with the walls 95 of said passages, a finger-piece for the push button mounted on said body portion and carrying a connector for bridging said contact terminals.

3. A push button comprising a body portion having separate passages therein, a pair of spring contact terminals consisting of folded spring contacts fitted into said passages and held in position therein by their tension, and a finger-piece carrying a 100 U-shaped connector adapted to bridge said spring contacts.

4. A push button comprising a body portion having two separate passages formed therein adjacent the bottom thereof, a pair 110 of spring contact terminals positioned within said passages, said body portion having two other passages communicating with the said two first mentioned passages, and a finger-piece carried by said body portion 115 having a two-legged connector, the legs of which are located in said last mentioned passages and are adapted to bridge the contact terminals.

In witness whereof I subscribe my signature, in the presence of two witnesses.

DAVID E. BLAIR.
